UNITED STATES PATENT OFFICE

WILLIAM M. BECK, OF ELWOOD, INDIANA, ASSIGNOR OF ONE-HALF TO WILTON L. HIBBERD, OF ELWOOD, INDIANA

ELECTRIC TRAIN CONTROL

Application filed August 9, 1927. Serial No. 211,819.

This invention relates in general to an automatic train control and in particular to an electrically operated control which may be actuated in combination with the usual and well known automatic electric block signal system as now commonly employed on railroad systems.

The invention is equally well adapted to electrically, steam or gas driven vehicles which are operated on tracks, and the equipment necessary to adapt the control to any vehicle is exceedingly simple and may be installed without any radical change in the present design of the rolling stock or block signal systems.

The invention is here described in one specific form as applied to a locomotive, with reference being made to the accompanying drawings, in which—

Fig. 1 is a diagrammatic view of the new equipment which is carried by the locomotive.

Fig. 2, an enlarged wiring diagram of the hook-up of the equipment carried by the locomotive; and

Fig. 3, a complete wiring diagram of two blocks protected by an automatic signal system to which the hook-up is added to complete the invention.

Like characters of reference indicate like parts throughout the several views.

Referring to Fig. 1, where a locomotive is indicated by dash lines, a short section of track hereinafter termed a ramp 10 is carried to the right of and insulated from the railroad tracks 11, at the end of that section of track comprising what is termed a block—Fig. 3, showing two full blocks 12 and 13, and the ends of the adjoining blocks 14 and 15.

A brush 16 is carried at the side of and insulated from, the locomotive. The brush 16 is raised and lowered out of and into contact with the ramp 10 in accordance with the rate of travel of the locomotive. A fly-ball gov-

ernor 17 is geared to run directly from one of the axles 18 of the locomotive, and the shaft 19 is raised at predetermined slow speeds, such as would be employed by a locomotive in switching service about railroad yards, and is lowered with speeds thereabove so that the brush 16 suspended from the lever 21 pivoted to the shaft 19 is raised at the low speeds to be held above the ramp 10 as the locomotive passes thereby, and is lowered to contact and sweep over the ramp at the higher speeds.

Suitably mounted on the locomotive is a solenoid electro-magnet 22 which has the core 23 interconnected with the air-brake control handle 24 in such a manner that when the magnet 22 is energized, the handle 24 is pulled over to set the air brakes on the locomotive as well as on the cars being drawn by the locomotive (not shown).

This electro-magnet 22 is in circuit in series with a battery 25 and the contact points of the relay 26. A switch 27, while normally held closed, is included in the electro-magnet circuit as a means for breaking the circuit in emergencies. The electro-magnet circuit is normally held open by the relay 26.

One terminal of the relay magnetic coil is grounded through the frame of the locomotive and hence is in direct circuit with the tracks over which the locomotive passes. The other terminal of the relay coil is connected through the primary relay energizing battery 28 to the brush 16. The relay 26 may therefore be placed in operation by the battery 28, which is carried by the locomotive, by merely interconnecting the ramp 10 with the track to complete the circuit to energize the relay coil, close the relay contacts, and cause the battery 25 to energize the solenoid 22 to set the air brakes. As soon as the brush 16 has been carried beyond the ramp 10, the primary relay circuit is broken, which action causes said relay to break the solenoid circuit so that the air brake control handle 24 may be re-

turned manually to the release position. Should the locomotive stop so suddenly that the brush 16 comes to a stop on the ramp 10, the switch 27 may be pulled out to break the solenoid circuit and permit the brakes to be released so that the locomotive may proceed. A spring is provided (see Fig. 1) to throw the switch into contact to prevent the circuit being thoughtlessly left open.

Reference is now made to Fig. 3, in describing the method of connecting the ramp 10 and the track in circuit to close the relay circuit as above described.

The blocks 14 and 15 are here shown as without signal protection. At the end of the block 14 is the ramp 10 at the right hand side thereof with respect to the normal direction of traffic. The block 12, has the similar ramp 10'. To control a train proceeding in the opposite direction beginning with the block 15, 20 are the ramps 10'' and 10''' respectively, at the ends of the blocks 15 and 13.

The rails 30 and 31 are normally insulated one from the other and are interconnected by the track battery 29, and the multiple contact relay 32 is also interconnected between the rails 30 and 31, so that the relay electromagnet coils are normally energized by the track battery 29 to throw the current from the semaphore lamp battery 52 through the green lamp 33 as shown in Fig. 3, as a signal to trains in block 13 that block 12 is clear. Also a circuit is closed by the relay 32 to energize the relay 34 at the other end of the block 12, which relay 34 in turn closes the semaphore circuit from the battery 42 to the green lamp 35 to indicate to trains in block 14 that blocks 12 and 13 are clear.

It is to be noted, in Fig. 3, that when the relay 32 is energized by the track battery 29 as above described, a circuit 36 is broken, one wire of which goes to the rail 37 and the other to the ramp 10'''; and also that the relay 34 when energized from the relay 32, opens a corresponding circuit 38 including the ramp 10 and the rail 39.

Now assuming a train to enter the block 12 from the west, the track battery 29 will be short-circuited through the train wheels and axles with the result that no current will then flow from the battery 29 to the relay 32 whereupon relay 34 will likewise receive no current from the battery 52 as the armatures of the relay 32 are then dropped and the red lamp 43 will be illuminated.

Also when the current fails to come from the track battery 29, the armature 53 will drop back to throw the green lamp 33 out of the battery 52 circuit and to connect the red lamp 40 into the circuit, and also the relay armature 54 will drop back to close the circuit 36 between the ramp 10''' and the rail 37, the circuit normally being open between the ramp and the rail.

Similarly, when the current fails to flow to

the relay 34 at the other end of the block 12, the relay armature 55 will fall back to close the circuit 38 between the ramp 10 and the rail 39, and the relay armature 56 falls down and throws the green lamp 35 out of the circuit with the battery 42 and places the red lamp 43 in circuit with the battery 42. Therefore, it is seen that red lamps are shown at each end of the block 12, and that the ramps 10 and 10''' at each end of the block 12 are placed in circuit with the rails of the blocks 14 and 13. It is to be noted that there is no battery current thrown into the circuits 36 and 38, each of which while closed by their corresponding relays 32 and 34, are open between the ramps and the rails.

Should a train start to leave the block 14 and enter the block 12 while the red lamp 43 is burning, the brush 16 of the locomotive will contact the ramp 10, and as the wire 38 is already connected across the rail 39 and the ramp 10 through the armature 55, the circuit is completed through the locomotive to cause current to flow from the locomotive relay battery 28 to energize the locomotive relay 26 which in turn then closes the circuit of the solenoid 22 to set the brakes on the locomotive and bring it to a stop.

The diagram as shown in Fig. 3, indicates a block system wherein the lighting of the lamp 35 indicates the unoccupied condition of both block 12 and block 13. The lighting of the lamp 33 indicates the unoccupied condition of block 12 only, no signals being here shown for the block 14 which may be a yard track or any similar section where block control is not desired. The control over the ramps 10''' and 10 is here shown as corresponding to the indications of the lamps 33 and 35 in respect to the blocks as above indicated, the non-effective condition of 10''' indicating the unoccupied condition of one block only in advance, whereas the non-effective condition of 10 indicates the unoccupied condition of two blocks in advance. The control over the respective ramps is, therefore, not uniform, and it is pointed out that whether two blocks are indicated as unoccupied from one direction or only one block from the other, is immaterial to the invention herein claimed, since it is not the sequence of occupied and unoccupied blocks that is claimed but, instead, the means for indicating the condition of one or more blocks.

Owing to the brush 16 being lifted or lowered in association with the speed of the locomotive, it is possible for the locomotive to enter a danger block at a slow rate of speed, which action is desirable at times as it permits the train to proceed cautiously, where otherwise it would be unnecessarily delayed. By changing the elevation of the ramps from low positions in the local yards to higher positions out on the main track, the lifting device of the brush 16 is effective then only

in the yards, and the higher ramps out on the main track will contact the brush 16 at its highest elevation as well as its lowest.

Should the locomotive be travelling in re-

5 verse, the reverse lever (Fig. 1) when pulled back to reverse position closes the switch 45 to place a brush 46, on the left hand side of the locomotive into circuit with the battery 28 to function the same as the brush 16 does 10 when the locomotive is proceeding ahead. By employing this left hand brush in addition to the right hand brush 16, only one ramp need be placed at the end of each block and it can be uniformly placed on the right hand 15 side of the track with respect to the corresponding direction of travel.

Although the arrangement has not been shown, the battery 25 may be kept charged by the usual generator carried by the locomo- 20 tive.

It is obvious that the invention here described and shown in one particular form may be changed considerably in structural form without departing from the spirit of the invention, and I therefore do not desire to be limited to the precise structure, nor any more than may be necessitated by the following claims.

I claim:

30 1. In a block control system, the combination with a pair of rails forming a track, a ramp insulated from the track, a source of electric current permanently interconnected across said rails, a semaphore carrying means for selectively indicating occupied and unoccupied conditions of said track, a second source of current available to operate said semaphore means, and a relay interconnected across said rails, of a ramp switch controlled by said relay, said relay while under the influence of said first source of current affecting electrical circuits between said second source of current and said semaphore means to cause an unoccupied condition to be indicated, and said relay normally causing said ramp switch to remain open, and said ramp switch automatically directly connecting said ramp with one of said rails independently of said second source of current upon failure of said first source to affect said relay.

35 2. In a block control system, the combination with a pair of rails forming a track, a ramp insulated from the track, a source of electric current permanently interconnected across said rails, a semaphore carrying means for selectively indicating occupied and unoccupied conditions of said track, a second source of current available to operate said semaphore means, and a relay interconnected across said rails, of a ramp switch controlled by said relay, said relay while under the influence of said first source of current affecting electrical circuits between said second source of current and said semaphore means to cause an unoccupied condition to be indicated, and

said relay normally causing said ramp switch to remain open, and said ramp switch automatically directly connecting said ramp with one of said rails independently of said second source of current upon failure of said first source to affect said relay, and a train 70 adapted to move over the track, train control means carried by the train having a normally open actuating circuit, and terminal means carried by the train adapted to contact said ramp to close said actuating circuit through 75 said track and said ramp switch.

3. In a block control system, a pair of rails forming a track, a third rail relatively short in length, a track battery permanently interconnected between said pair of rails, an electrically operated semaphore, a relay having a coil interconnected across said pair of rails, a semaphore battery, a circuit having a switch controlled by said relay and including there- 80 in said semaphore battery and electrically operated semaphore means indicating an unoccupied condition of said track, a second circuit having a switch controlled by said relay and including therein said semaphore 85 battery and electrically operated semaphore means for indicating an occupied condition of said track, a third rail circuit having a switch controlled by said relay, said third rail circuit comprising a circuit between said 90 third rail and one of said track rails through said third rail switch open between said third rail and said track rail, said relay coil normally being energized by said track battery 95 to hold said first circuit switch closed and said second circuit and third rail switches open, and said second circuit and third rail switches automatically closing and said first circuit switch automatically opening upon failure of said track battery to supply current to said coil. 100

4. In a block control system, a pair of rails forming a track, a third rail relatively short in length, a track battery permanently interconnected between said pair of rails, an electrically operated semaphore, a relay having a coil interconnected across said pair of rails, a semaphore battery, a circuit having a switch controlled by said relay and includ- 110 ing therein said semaphore battery and electrically operated semaphore means indicating an unoccupied condition of said track, a second circuit having a switch controlled by said relay and including therein said semaphore 115 battery and electrically operated semaphore means for indicating an occupied condition of said track, a third rail circuit having a switch controlled by said relay, said third rail circuit comprising a circuit between said 120 ramp and one of said track rails through said third rail switch and open between said third rail and said track rail, said relay coil normally being energized by said track battery 125 to hold said first circuit switch closed and said second circuit and third rail switches open, 130

4

and said second circuit and third rail switches automatically closing and said first circuit switch automatically opening upon failure of said track battery to supply current to said coil, and train control means short circuiting said track battery and completing a control circuit between said third rail and said track rail.

In testimony whereof I affix my signature.
WILLIAM M. BECK.
